UNITED STATES PATENT OFFICE

LEONARD DE WIT, OF CHICAGO, ILLINOIS

DESIGN FOR A STATUETTE OR ANALOGOUS ARTICLE

Application filed February 3, 1932. Serial No. 42,722. Term of patent 7 years.

To all whom it may concern:

Be it known that I, LEONARD DE WIT, a citizen of the United States, and resident of Chicago, in the county of Cook and State of Illinois, have invented a certain new, original, and ornamental Design for a Statuette or Analogous Article, of which the following is a specification, reference being had to the accompanying drawing, forming a part thereof.

In the drawing:

Fig. 1 is a front elevational view of a statuette or analogous article, showing my new design;

Fig. 2 is a side elevational view thereof; and

Fig. 3 is a rear elevational view from the opposite side thereof.

I claim:

The ornamental design for a statuette or analogous article as shown.

In witness whereof, I hereunto subscribe my name this 30th day of January, 1932.

LEONARD DE WIT.
